UNITED STATES PATENT OFFICE.

WILLIAM I. ROSENFIELD, JR., OF NEW YORK, N. Y.

DESIGN FOR A BADGE OR LIKE ARTICLE.

Application filed January 8, 1925. Serial No. 11,964. Term of patent 3½ years.

To all whom it may concern:

Be it known that I, WILLIAM I. ROSENFIELD, Jr., a citizen of the United States of America, residing at 562 Fifth Avenue, in the city, county, and State of New York, have invented a new, original, and ornamental Design for Badge or like Article, of which the following is a specification, reference being had to the accompanying drawing, forming part thereof.

Figure 1 is a front view of the badge or like article.

Figure 2 is a back view thereof.

Figure 3 is an edge view.

As shown in Figures 1 and 2, the letters of the wording "I love you" are cut clear through the metal plate, as are also certain other parts of the plate so as to provide square openings therethrough, all contributing to give a novel appearance to the badge or like article.

What I claim is:

The ornamental design for a badge or like article as shown and described.

WILLIAM I. ROSENFIELD, JR.
